COUPLING NUT

Fred R. Long, Catawissa, Pa.

Application July 30, 1936, Serial No. 93,473

2 Claims. (Cl. 85—32.1)

This invention relates to pipe couplings and more particularly to an improved coupling ring or nut having novel tool engaging faces.

While it has been heretofore proposed to provide nuts or couplings with various forms of tool engaging faces or members, nevertheless, in many instances such devices are impractical for general use because they do not provide either a proper purchase for the applying tool, or are so constructed as to become easily broken when subjected to a hammer blow in either driving the coupling nut home or releasing it to separate the union.

Accordingly, a primary object of the present invention is to provide a coupling ring or so-called lug nut having a substantial body portion formed exteriorly with a plurality of angularly related faces for a portion of the depth thereof while the remainder of such depth is formed with radially projecting lugs of special formation. These lugs project sufficiently beyond the maximum diameter of the body to afford proper anvil faces and also adequate leverage not only to convert a hammer blow or the like into rotary motion but also to distribute the force of the blow to opposite sides of the body to avoid breakage of the lugs.

A further object of the invention is to provide a lug nut or coupling which may also function as a pipe hanger when used in connection with a support.

With the above and other objects in view which will more readily appear as the nature of the invention is better understood, the same consists in the novel construction, combination, and arrangement of parts hereinafter more fully described, illustrated and claimed.

A preferred and practical embodiment of the invention is shown in the accompanying drawing in which:—

Fig. 1 is a perspective view illustrating the application of the invention.

Fig. 2 is a side elevation of the present improvement.

Fig. 3 is a top plan view of the invention installed for use, portions of the same being broken away to more completely illustrate the mode of application and utility.

Fig. 4 is a detail cross section illustrating the utility of the improvement as a pipe hanger.

Fig. 5 is a side elevation of the construction shown in Fig. 4.

Similar reference characters designate corresponding parts throughout the several figures of the drawing.

In the embodiment of the invention shown in the accompanying drawing the same includes in its organization a body designated generally as 1, which is of annular formation having an internally threaded portion 2 for engaging with the threads 3 of one portion of a pipe coupling and the interior annular shoulder 4 for engaging with a rib or shoulder on the mating part of the coupling.

The body is externally provided with a plurality of tool engaging portions designated generally as A and B arranged in adjacent relation transversely of the axis of the body thereby to enable the body to be engaged by either a wrench or a hammer for imparting rotary or turning movement thereto.

The tool engaging portion A preferably comprises a plurality of flat contiguous angularly related faces 5 which may in effect provide a hexagonal or other form of nut adapted for wrench engagement. The said faces 5 are disposed in tangential relation to the annular face 6 of the body. Adjacent to the said angularly related faces 5 the body is provided with the tool engaging portion B, namely, the offset wings 7—7 which are of substantially triangular formation with the apices 8 thereof extending outwardly beyond the body and considerably beyond the faces 5 as will be apparent from the drawing. The side edges of the triangular extensions 7—7 form anvil faces 9 which diverge inwardly from the apices 8 toward the body so that the anvil faces of opposite triangular members not only meet as indicated at 10 but said faces lie substantially tangentially to the annular body portion 6 previously referred to.

From the foregoing it will be apparent that the body of the nut or ring is provided for a portion of its depth along its axis with contiguous angularly related faces and for the remainder of its depth is provided with the triangular lug extensions. This arrangement makes it possible for a wrench to have free access to the tool engaging portion A without interference from the triangular lugs 7 and also makes it possible for a hammer (indicated in dotted lines in Fig. 1) to have adequate purchase on the anvil faces 9 of the triangular lugs without interference from the wrench engaging portion. Thus, when it is desired to tap the coupling home it will be apparent that the force of the hammer blow is distributed over substantially 180 degrees of the circumference of the annular or ring-like body thereby effectively to impart the full force of the blow to the coupling body without breaking

the lug and at the same time obtaining the full benefit of the blow in completely seating the coupling. The triangular lugs 7 are therefore a distinctive feature of the invention. Moreover, 5 their location with relation to the wrench engaging portion has the advantage of making it possible to use a wrench and hammer simultaneously, if desired.

A further practical advantage of the lugs 7 is 10 that they may provide a pipe hanger as illustrated in Figs. 4 and 5. For example, suitable bracket means including the arms or pins 11—11 may be secured to a support and the lugs 7—7 may rest thereon. In the example shown the 15 arms or pins 11—11 may be formed from a single U-shaped piece of metal. The supports may be placed at the location of the lugs wherever the union happens to be located and will effectively prevent retrograde movement of the pipe line. 20 The distinctive feature is that the coupling has outwardly extending means for engaging a support.

I claim:—

1. A coupling nut comprising an annular body including internal threads and having its external portion provided with a plurality of angularly disposed tool engaging faces over a part 5 of its axial depth, said body also provided over the remainder of its axial depth with laterally extending lugs having anvil faces disposed outwardly of said first mentioned faces, said anvil faces diverging inwardly and having their inner 10 portions substantially tangential to the maximum diameter of the body.

2. A coupling nut including a substantially annular body formed transversely with separate adjoining tool engaging surfaces one of which is 15 diamond shaped providing four angularly related anvil faces, and the other of which is hexagonal with four of its faces lying in the same plane as the anvil surfaces.
